UNITED STATES PATENT OFFICE.

FRIEND W. SMITH, JR., OF BRIDGEPORT, CONNECTICUT, ASSIGNOR TO
THOMAS P. TAYLOR, OF BRIDGEPORT, CONNECTICUT.

HOSE-SUPPORTER.

SPECIFICATION forming part of Letters Patent No. 780,734, dated January 24, 1905.

Application filed October 6, 1904. Serial No. 227,306.

To all whom it may concern:

Be it known that I, FRIEND W. SMITH, Jr., a citizen of the United States, residing at Bridgeport, in the county of Fairfield and State of Connecticut, have invented certain new and useful Improvements in Hose-Supporters; and I do hereby declare the following to be a full, clear, and exact description of the invention, such as will enable others skilled in the art to which it appertains to make and use the same.

My invention relates to certain improvements in hose-supporters, but more particularly has reference to that class of such devices which comprises a flexible pad adapted to be secured in position by means of a belt passed around the waist of the wearer.

The object of my invention is to provide means for holding the pad as against any sidewise shifting and also to prevent the pad from slipping upward beyond the proper limit; and with these ends in view my invention consists in certain details of construction and combination of parts, such as will be hereinafter fully set forth and then specifically designated by the claims.

In the accompanying drawings, which form a part of this application, Figure 1 is a front elevation showing my improvement as it appears when secured in proper position on a corset; Fig. 2, a detail rear view of the pad shown at Fig. 1; Fig. 3, a section at the line *xx* of Fig. 1; Fig. 4, a detail rear view of a pad equipped with a modified form of my improvement, and Fig. 5 a section at the line *yy* of Fig. 4.

Similar numbers of reference denote like parts in the several figures of the drawings.

In supporters of this kind a large cloth pad has been provided, at the upper corners of which a buckle and belt-strap have been secured, so that the pad may be suspended around the waist of the wearer without any other attachment to the corset itself, while the hose-supporter elements proper depend from the bottom edge of this pad. In using a construction of this sort a great annoyance has been experienced owing to the fact that the pad would shift sidewise and would not hang in proper position immediately in front of

the busk-sections of the corset. Also when the wearer was in a sitting position the pad would ride upwardly over the bottom clasp of the corset and would frequently catch upon said clasp. My invention aims to overcome these disadvantages and at the same time to allow the pad to have a vertical play between certain limits and also to be capable of a free rocking movement, so as to respond to the action of the limbs of the wearer.

1 represents the sections of an ordinary corset, and 2 the busks thereof, which are usually secured together by means of metal clasps, which latter comprise a loop secured to one busk and a stud secured to the other busk. At Fig. 1 I have shown one of these clasps in dotted lines in the immediate rear of the pad of my supporter, said loop and stud being respectively denoted by the numerals 3 and 4.

5 represents a large flexible pad, usually made of cloth, and secured to the upper corners of this pad are a belt-strap 6 and a buckle 7, by means of which the pad is secured around the waist of the wearer, as shown in the drawings. I have not shown the hose-supporter elements proper, since they form no part of my present invention; but I have merely shown short sections 8, which represent the hose-supporter tapes secured to the bottom of the pad, and I desire that it be understood that any suitable number of hose-supporter tapes of any preferred form of construction may be secured to the bottom of the pad.

Projecting from the rear of the pad is a shank 9, surmounted by an overhanging head 10, the base of said shank being secured to the pad in any suitable manner. In utilizing my improvement this head 10 is inserted at the bottom edges of the corset behind the busks, the shank 9 being interposed between the meeting edges of said busks, and when the pad has been secured by means of the belt and buckle aforesaid this head will be drawn very close if not quite up to the bottom clasp of the corset, and it will therefore be very readily understood that the pad cannot possibly be displaced sidewise and that it cannot ride upwardly beyond a proper limit, owing to the abutment of the shank 9 against the

corset-clasp. Furthermore, it will be noted that the pad is capable of a rocking movement with the shank 9 as a pivot, while at the same time a free vertical play of the pad is 5 permitted, so that said pad is in no sense secured to any part of the corset.

There are several ways in which my improvement may be constructed, but in all instances it is necessary that a flanged element 10 should be employed at the rear of the pad capable of being inserted immediately behind the corset-busks. For instance, at Fig. 4 I have shown a metal body 11 secured to the rear of the pad 5, the free end of this body 15 being bent upwardly so as to form a flange or tongue 12, as shown more particularly in section at Fig. 5, which flange would be inserted at the bottom of the corset immediately in the rear of the corset-busks, so as to perform the 20 same function in substantially the same manner as in the instance of the construction shown at Fig. 2. I prefer, however, to utilize the construction shown at Fig. 2, since it is neater and more compact; but I do not wish 25 to be limited in this respect, since my invention contemplates, broadly, a device extending from the rear of the pad and capable of being loosely engaged with the corset in the immediate rear of the busks, so as to center 30 the pad and hold the same as against displacement in any direction.

Having thus described my invention, what I claim as new, and desire to secure by Letters Patent, is—

35 1. A hose-supporter comprising a flexible pad, a sole means of suspension consisting of a belt attached to said pad and adapted to be passed around the waist of the wearer, and a device independent of said means of suspension and carried by said pad at a point below 40 said means of suspension and adapted to be loosely engaged with the corset in the rear of the busk-sections thereof.

2. In a hose-supporter, a flexible pad, a sole means of suspension consisting of a belt attached to the upper corners of said pad and adapted to be secured around the waist of the wearer, and a keeper device independent of said means of suspension and secured to the pad at a point below said means of suspension 45 and having a flanged element extending from the rear of said pad and adapted to be inserted loosely between the busks and in the immediate rear thereof and below the bottom corset-clasp. 50

3. A hose-supporter comprising a flexible pad, a sole means of suspension consisting of a belt attached to the upper corners of said pad and adapted to be secured around the waist of the wearer, and a metallic base portion secured to the rear of the pad and having projecting therefrom at a point below said means of suspension a flanged element adapted to be loosely contained in the immediate rear of the corset-busks and below the bottom 65 corset-clasp. 60

4. In a hose-supporter, a flexible pad, a waist-belt attached to the upper corners of said pad, and a metallic base secured to the pad and having a shank surmounted by an 70 overhanging head projecting slightly beyond the rear face of said pad at a point below said means of suspension, said head adapted to be inserted from the bottom of the corset in the immediate rear of the busks thereof, while 75 the shank is interposed between the meeting edges of said busks, said head and shank being at all times independent of said means of suspension and below the bottom corset-clasp and capable of a free vertical play. 80

In testimony whereof I affix my signature in presence of two witnesses.

FRIEND W. SMITH, JR.
